UNITED STATES PATENT OFFICE.

CHRISTOPHER E. HERTLEIN, OF NEW YORK, N. Y.

DESIGN FOR GIMP.

SPECIFICATION forming part of Design No. 22,279, dated March 14, 1893.

Application filed January 28, 1893. Serial No. 460,168. Term of patent 3½ years.

To all whom it may concern:

Be it known that I, CHRISTOPHER E. HERTLEIN, a citizen of the United States, residing at the city of New York, county and State of New York, have invented and produced a new and original Design for Gimp, of which the following is a specification, reference being had to the accompanying drawing, in which—

The figure shown in the drawing is a view of a piece of gimp showing my design.

The leading features of my design for gimp consist of a series of narrow or stem-like portions, alternating with enlarged portions which are connected to borders, one on each

side by cords or threads. The stem-like portions 1, and enlarged portions 2, have the appearance of cord wound around them. The borders or braid 3 and 6 are connected by cords 4, 5, 7 and 8 between the enlarged portions and the said borders as shown. 15 20

What I claim is—

The design for gimp, substantially as herein shown and described.

CHRISTOPHER E. HERTLEIN.
